UNITED STATES PATENT OFFICE.

ARTHUR E. DULMAGE, OF OBERLIN, OHIO, ASSIGNOR TO THE BUCKEYE CREAM SEPARATOR COMPANY, OF SAME PLACE.

DESIGN FOR A WATER-SPRAYING STAND FOR CREAMERY-CANS.

SPECIFICATION forming part of Design No. 30,574, dated April 18, 1899.

Application filed March 22, 1899. Serial No. 710,099. Term of patent 7 years.

To all whom it may concern:

Be it known that I, ARTHUR E. DULMAGE, a citizen of the United States, residing at Oberlin, in the county of Lorain and State of Ohio, have invented and produced a new and original Design for a Water-Spraying Stand for Creamery-Cans, of which the following is a specification, reference being had to the accompanying drawings, forming part thereof.

Figure 1 is a plain elevation of my new water-distributing stand, and Fig. 2 is a plan view thereof.

As shown in the drawings, the leading or material feature of my design consists in the upright portion A, the same being fashioned after the manner of a plain tube or column in all outward appearance and design and having a plain smooth surface 2 down some distance from its upper end and a lower surface 3, ornamented all around with perfora-

tions evenly distributed over the same and extending from said plain surface 2 downward toward the lower end of the tube, so that as the design presents itself to the eye of an observer he sees especially a tubular column having a surface bearing the peculiarities shown and described. The complete design comprises this novel appearing column and a practically plain-surfaced base B, on the center of which the column is erected.

What I claim is—

The design for a water-spraying stand for creamery-cans, substantially as shown and described.

Witness my hand to the foregoing specification this 18th day of March, 1899.

ARTHUR E. DULMAGE.

Witnesses:

W. B. BEDUTHA,
BERTHA ECKERT.
